The ornamental design for a wireless router, as shown and described.

DESCRIPTION

FIG. 1 is a bottom view of a wireless router;
FIG. 2 is a top view thereof;
FIG. 3 is a right side view thereof;
FIG. 4 is a front view thereof;
FIG. 5 is a left side view thereof;
FIG. 6 is a back view thereof; and,
FIG. 7 is a front perspective view thereof.
